UNITED STATES PATENT OFFICE.

BEHREND ULFERTS, OF LAKEFIELD, MINNESOTA.

AUTOMATIC ALARM SYSTEM.

1,211,644.

Specification of Letters Patent.

Patented Jan. 9, 1917.

Application filed July 27, 1915. Serial No. 42,135.

To all whom it may concern:

Be it known that I, BEHREND ULFERTS, a citizen of the United States, residing at Lakefield, in the county of Jackson and State of Minnesota, have invented certain new and useful Improvements in Automatic Alarm Systems, of which the following is a specification.

This invention relates to an automatic train-controlled alarm system for use by electric and steam railways for the purpose of indicating to the engineer of a train approaching a switch point whether or not, by the action or non-action of the signal mechanism, the switch is open or closed, so that in the event of the switch being open and an alarm being given the engineer may bring his train to a stop in ample time to prevent danger.

The object of the invention is to provide a signal system of this character embodying a simplified construction of operating parts, whereby an alarm system is produced which may be inexpensively installed and maintained and which is not liable to easily get out of order.

A further object of the invention is to provide an electric alarm system of the character described including a third rail arranged within the alarm system and adapted to be engaged by a contact device on the locomotive, which contact device is of a construction adapted to clear the rail of snow, ice or any other surface coating and to insure a proper contact therewith to energize the alarm circuit when the switch is in open position.

The invention consists in the features of construction, combination and arrangement of parts hereinafter more fully described, reference being had to the accompanying drawings, wherein—

Figure 1 is a plan view of a section of a railway track at the switch point, showing the parts as they appear when the switch is closed; Fig. 2 is a similar view, showing the parts as they appear when the switch is open and the alarm circuit thrown into action; Fig. 3 is a view in elevation, partly in section, of the switch stand, showing the contacts in engagement to close the alarm circuit; Fig. 4 is a sectional plan view on line 4—4 of Fig. 3; Fig. 5 is a side elevation of the contact device upon the locomotive; Fig. 6 is a top plan view of the same; and Fig. 7 is a detail view of the hanger or sus-

pending rod whereby the contact device is flexibly supported.

Referring to the drawings, 1 and 2 designate the main line rails of a track adjacent to the switch point, and 3 and 4 the movable switch rails forming the switch point and which are connected for movement in unison by the throw bar 5. This throw bar 5 extends at one end beneath the track to a switch stand 6, and is connected to a crank arm 7 on the lower end of a shaft 8 journaled in the switch stand casing 9 and carrying a target or other suitable visual signal 10.

The switch stand shaft 8 and its casing 9 are arranged in and form part of an electric circuit including conductors 11 and 12. The conductor 11 is connected with a contact 13 on the shaft 8 and extends therefrom to one of the main line rails, while the conductor 12 is connected at one end with a contact 14 carried by and insulated from the casing 9, and extends therefrom to a third rail 15 disposed between the main line rails 1 and 2 at a suitable distance from the switch point. When the switch is in closed position, the contacts 13 and 14 are out of engagement with one another, so that the circuit remains unaffected in the travel of the train toward the switch point, but in the event of the switch being accidentally or otherwise left open the contacts 13 and 14 will engage and place the electric circuit in condition to be closed to operate the warning signal.

Arranged within the cab of the locomotive is a signal bell or device 16 which is connected by a conductor 17 with the axle 21', the conductor 11 being connected to the rail 2 and from the rail to the axle 21'. The conductor 18 from the signal device 16 passes to a battery or other source of electric supply 19. The other pole of this battery is connected by a conductor 20 with a contact device 21 supported upon the locomotive and arranged for co-operation with the third rail 15. The conductor 17, in practice, makes electrical connection with the rail 1 through one of the axles 21 of the locomotive and the wheels 22 carried by the axle, the wheels and axle also serving to connect the alarm device through said contact device with the circuit connections 11, 12, 13, 14 and 15 when the contact device is in engagement with the rail 15 and the contacts 13 are in engagement with each other.

Assuming that a train is running along the main line rails toward the switch point, it will be understood that if the switch is closed, as it should normally be, the contacts 13 and 14 will be separated and consequently the circuit will remain broken in the travel of the contact 21 over the rail 15, the alarm device 16 hence remaining silent and indicating by its silence that the switch 5 is in proper position for safe travel. If, on the other hand, the switch should be open, the contacts 13 and 14 will be in engagement with each other and hence when the contact device 21 on the locomotive comes into engagement with the rail 15 a circuit will be established, the current passing from the battery through the conductor 18 to the bell 16 and sounding the latter, and thence through the conductor 17 and through axle 20 21 and its wheels 22 to the rail 2, thence through the conductor 11 to the contact 13, and through the contact 14 and conductor 12 to the third rail 15, and through the contact device on the locomotive back again to 25 the battery, the alarm being sounded at a sufficient distance from the open switch point to warn the engineer of the impending danger and to enable him to stop his train in time.

30 The contact device 21 is of simple form and comprises a vertically movable arm or bar 23 which is hinged or pivoted at one end, as at 24, to a bracket 25 secured to a suitable point of one of the truck frames of the locomotive. 35 The opposite or free end of this arm or bar 23 carries a weighted block 26 of wood or other electrical insulating material, which is bifurcated at its free end and provided with bearings 27 for a shaft or axle 28 carrying 40 a contact wheel 29. This contact wheel is adapted to engage the third rail or contact rail 15 to close the circuit and is provided with a beveled edge 30 forming practically a knife surface which will cut from the 45 surface of the contact rail any ice, snow or other foreign material which may be adhering thereto, thus insuring a perfect contact being made. The weighted arm 23 is adapted to normally maintain by gravity a 50 position to dispose the wheel 30 for engagement with the rail 15 but is yieldingly mounted for vertical movement to prevent injury to the contact device if it should come into engagement with any foreign obstruction, as well as to adapt it to conform 55 to any irregularities or surface of the rail 15 without becoming broken or damaged. To this end the arm 23 is pivoted, as indicated, and is suspended at its free end 60 loosely upon the lower end of a rod 31 which passes downwardly therethrough and is provided with an abutment surface 32,

the upper end of the rod being provided with a cross piece or head 33 which slidably and pivotally engages a slotted bracket 34 upon the locomotive, the rod thus being mounted to swing to a certain extent to accommodate itself to and permit the arm 23 to have vertical motion through a predetermined arc. A coiled cushioning spring 35 surrounds the rod 31 between the block 26 and bracket 34 and serves to yieldingly oppose any upward movement of the weighted arm, thereby adapting it to recede easily when engaging the contact rail or an obstruction and to accommodate itself to irregularities in the surface thereof, thus obviating any danger of the contact device being broken or otherwise injured in normal service.

From the foregoing description, taken in connection with the drawings, the construction and mode of operation of my improved safety signal will be readily understood, and it will be seen that the invention provides a signal of this character which is not only simple of construction and reliable and efficient in action, but which may be installed and maintained at a comparatively low cost and contains comparatively few parts, of a character not liable to easily get out of order. It will be evident that under normal conditions the circuit will remain open, thus giving by its silence indication of the fact that the switch is properly set, but that, should the switch be accidentally left open or opened by a malicious person, the circuit will be automatically set so as to be closed by the closing device on the locomotive to sound the warning signal and give the engineer notice of the condition of the switch.

I claim as my invention:

In an alarm circuit of the character described and in combination with an electrical circuit adapted to be set for closure under prescribed conditions, means for closing said circuit comprising a contact rail and a contact device upon the locomotive, said contact device including a bar pivotally mounted at one end thereof, an insulation block carried by the swinging end thereof, a contact wheel carried by the swinging end of the bar, a suspension rod loosely connected with said bar and slidably and pivotally supported from the locomotive and a cushioning spring associated with said suspension rod.

In testimony whereof I affix my signature in the presence of two witnesses.

BEHREND ULFERTS.
